(57) **CLAIM**

The ornamental design for a vehicle exhaust conduit, substantially as shown and described.

DESCRIPTION

FIG. 1 is a right side, and top, perspective view of a vehicle exhaust conduit showing my new design;

FIG. 2 is a right side elevation view thereof;

FIG. 3 is a left side elevation view thereof;

FIG. 4 is a front elevation view thereof;

FIG. 5 is a rear elevation view thereof;

FIG. 6 is a top plan thereof;

FIG. 7 is a bottom view; and,

FIG. 8 is a side elevation view thereof in association with an exemplary vehicle.

The portions of the vehicle exhaust conduit shown in dotted lines do not constitute a part of the claimed design.
